UNITED STATES PATENT OFFICE.

WILLIAM SCHMITT, OF SULLIVAN, MISSOURI.

DESIGN FOR A DISPLAY-RACK.

48,915.

Specification for Design.

Patented Apr. 18, 1916.

Application filed December 29, 1915. Serial No. 69,294. Term of patent 7 years.

To all whom it may concern:

Be it known that I, WILLIAM SCHMITT, a citizen of the United States, residing at Sullivan, in the State of Missouri, have invented a new, original, and ornamental Design for Display-Racks, and of which the following is a specification, reference being had to the accompanying drawing, forming part thereof.

Figure 1 is a view in elevation of a display rack illustrating my new design. Fig. 2 is a plan view.

I claim:

The ornamental design for a display rack, as shown.

WILLIAM SCHMITT.

Witness:

C. Z. LYNCH.
